UNITED STATES PATENT OFFICE.

HENRY MANRODT, OF NEWARK, NEW JERSEY, ASSIGNOR TO VERNIE R. SHATTUCK, OF PITTSBURGH, PENNSYLVANIA.

SLIP-SHEETING MACHINE.

Application filed July 12, 1928. Serial No. 292,239.

My invention relates to improvements in slip sheeting machines, and it more especially consists of the features pointed out in the annexed claims.

5 The purpose of my invention is to provide a slip sheeting device for use in connection with stencil duplicating machines, such as mimeographs, neostyles, etc., and other printing machines, such as multi-
10 graphs, etc., in a simple and efficient manner; that automatically collects the printed sheets on a moving band of porous paper and continuously holds the sheets between adjacent layers of the paper as it is wound
15 up onto itself; that delivers the sheets from a wound-up roll of paper to a suitably placed tray as the paper is rewound on a second roll; that provides means for the replacement of rolls as needed; that pro-
20 vides means for positively driving the receiving roll of porous paper in one direction and simply freeing such roll to permit the paper being unwound therefrom onto another roll, which in turn may if desired
25 thereafter be used to also receive printed sheets; and that permits the interchange of empty and full rolls.

With these and other ends in view, I illustrate in the accompanying drawings such 30 instances of adaptation as will disclose the broad underlying features of my invention without limiting myself to the specific details shown thereon and described herein.

Figure 1 is a side elevation of my device 35 showing the parts in the "slip sheeting" relation.

Fig. 2 is a side elevation showing the parts in delivery relation.

Fig. 3 is an elevation of a removable 40 roll supporting bracket.

Fig. 4 is a diagrammatic top plan view of Fig. 1 in reduced scale.

In practically carrying my device into 45 use, I may employ whatever alternatives of construction the exigencies of varying conditions may demand without departing from the broad spirit of my invention.

In the example instance in the drawing, my device may comprise a pair of vertical standards 10^a to which is attached a 50 pair of horizontal members 10^b. These members and standards constituting a frame 10 are held in spaced apart relation in any suitable manner. The members 10^b rest on table T where they may be held by any de-

sired clamps or otherwise so as to hold the slip sheeting device against accidental displacement. On the table T a duplicating device P may be located which is driven in any suitable manner (not shown).

60 The slip sheeting feature of my device comprises a receiving roller or driven drum 13^a having suitable heads 13 and a reserve roller or idle drum 14^a having suitable heads 14. These rolls or drums 13^a and 14^a are 65 removably supported in brackets 23 and 23^a formed on removable plates 24 which plates are attached to the standards 10^a. In order to adapt the device to tables of different heights the standards 10^a may have adjustable legs 10^b. If for any reason it is desired 70 to easily remove the plates 24 this may be done by sliding them vertically from under headed bolts 10^c, which bolts pass through openings or slots 24^a formed 75 in the plates. A suitable idling guide roller 12 is supported by a pair of brackets 11 which are attached to the members 10^b by bolts and wing nuts 11^a.

80 In the slip sheeting position of the parts shown in Fig. 1, the brackets 11 are supported on the top side of the members 10^b near their extreme end and when the parts of the device are in the delivery position shown in Fig. 2 the brackets 11 are secured 85 on the under side of the members 10^b adjacent the standards 10^a. If desired, the brackets 11 may be joined together in any well known manner so as to be handled as a unit and the method of fastening them in 90 one position or the other may be modified in any suitable manner to supplement or replace the wing nuts 11^a.

95 The band of paper 15^a which is more or less porous is taken from the roll 14^b and passed between the members 10^b, the brackets 11, over the roller 12, on a horizontal plane 15 across a tray 16 which prevents sagging of the band, onto the receiving drum 13^a where it is wound up at 13^b as the roller 13 is rotated by a belt 18 driven from the printing device P by a grooved pulley 19 cooperating with a grooved pulley 19^a that cooperates with the outer end of the shaft 13^c of the drum 13^a to rotate it. The belt 18 may 100 engage an idling pulley 18^b that may be adjusted vertically at the upper end of a standard 18^c which is suitably supported on one of the members 10^b or otherwise. This idler 18^b may serve as a tightener of the belt 18 110

by adjusting and holding it on the standard 18° in any desired manner. When the drum 13^a is to be no longer driven the belt 18 may be simply lifted from off the grooved pulley 18^b thus loosening the belt 18 on the grooved pulley 19^a without disengagement therefrom. When the drum 13^a is to be again rotated by the duplicator P the belt 18 is replaced on the idler 18^b.

10 The delivery relation of parts shown in Fig. 2 includes a removable receiving tray 21 that may be supported from one or both of the members 10^b by suitable rods 22 or otherwise. The tray 16 is positioned above the members 10^b on suitable supports 17. The drums 13^a and 14^a with their attached heads respectively 13 and 14 are positioned between the standards 10^a with their shafts or spindles 13^c and 14^c in the bearings 23 and 20 23^a.

25 The operation of my device is extremely simple. As the printed sheets are delivered tangentially from the duplicator P, indicated at *x* Fig. 1, they fall on the band 15^a on a horizontal plane within the sides of the tray 16, and are then successively carried by the band 15^a as it is wound at 13^b on the drum 13^a, the reserve portion of the band 15^a being taken from the roll of paper 14^b 30 from off the idling drum 14^a until it is entirely freed from the latter drum. When the printed sheets have remained on the receiving roll long enough to become dry the free end of the band is passed around the idler 12 in its new position, shown in Fig. 2, and then fastened to the drum 14^a in any well known manner. Thus secured the band is wound onto the drum 14^a by means of a handle 20 removably attached to the outer 35 end of the shaft 14^c of this drum. As the band is wound onto the drum 14^a from off the drum 13^a the printed sheets are delivered from the idler 12 at *y* onto the receiving tray 21.

40 45 Should it be found desirable to make the drums interchangeable I may use whatever expedients are found necessary to accomplish this purpose. I am aware that bands of porous paper have been used with winding rolls for slip sheeting purposes, but do not know that my arrangement of parts cooperating with the rolls or drums have been used heretofore, and that by reason of such relation I secure new results of great 50 practical value without recourse to expensive and complicated equipment.

55 What I claim is:

1. In slip sheeting devices, a frame, a pair 60 of reversible paper holding rolls supported on the frame, a band of porous paper in attachable and detachable engagement with the rolls on its one face, an idler adapted to engage the band on its opposite face, and means for supporting the idler in different 65 positions on the frame parallel to the rolls

in accordance with changes in direction of movement of the band.

2. In a slip sheeting device, a pair of reversible paper holding rolls, an idling roller in parallel relation to the rolls, a frame for supporting the rolls, means for supporting the idling roller in different positions on the frame, and a band of porous paper in engagement with the rolls and the idling roller on its opposite faces respectively. 75

3. In a slip sheeting machine, a frame, the combination with a duplicating mechanism, of a pair of paper receiving rolls supported in parallel relation to each other on the frame and reversible in respect of the rotation of the duplicating mechanism, an idling roller, means for supporting the idling roller in different positions on the frame between the paper receiving rolls and the duplicating mechanism, and a band of paper engaging 80 the rolls and the idling roller respectively on its opposite faces. 85

4. In a slip sheeting device, a duplicating device adapted to successively imprint separate sheets of paper and deliver such sheets 90 in orderly sequence independently of each other, comprising a frame, a band of porous paper adapted to receive the sheets on its one face, a reversible roll supported on the frame for winding thereon the band of porous paper, a reversible roll also supported on the frame for unwinding the paper therefrom, means for rotating the winding roll in unison with the duplicating device, and means comprising an idling roller adjustable on the frame to different positions for holding the band of paper substantially horizontal between the duplicating device and the winding roll. 95

5. In slip sheeting machines, a duplicating device comprising a frame, a pair of reversible rolls or drums supported on the frame, a band of ink receiving paper attachable to and removable from the drums, means for delivering imprinted sheets from the duplicating device tangentially and delivering them onto the band while the band is substantially on a horizontal plane, means for imparting movement to the band to wind it with its imprinted sheets onto one of the rolls, an idling roller adjustable to different positions on the frame engaging the band on its other face, and means for moving the paper in an opposite direction to wind it onto the other roller. 105 110 115

6. The combination with a duplicator or the like, of a slip sheeting attachment comprising a frame carrying a drum to be driven from said duplicator, an idle drum supported on the frame, guiding means adjustable to different positions on the frame, and a flexible band of porous paper traveling from the idle drum to the driven drum over said guide means and forming a moving support adapted to successively receive 120 125 130

and feed the sheets from said duplicator onto said driven drum and envelope them between the different layers of the band as the latter is being rolled onto the driven drum.

7. The combination with a duplicator or the like, of a slip sheeting attachment comprising a frame which consists of an upright for carrying said drums and a hori-

zontal part carrying the guiding means 10 adapted to be placed in different positions on the frame which is capable of being supported by the support of said duplicator so that the sheets dropping from the duplicator will be received by said band on a 15 horizontal plane.

In testimony whereof I affix my signature.
HENRY MANRODT.
